UNITED STATES PATENT OFFICE.

HARRY EVERETT McMULLEN, OF HUTCHINSON, KANSAS.

HOLLOW STEEL TIE.

No. 868,215.

Specification of Letters Patent.

Patented Oct. 15, 1907.

Application filed February 12, 1907. Serial No. 357,030.

To all whom it may concern:

Be it known that I, HARRY EVERETT McMULLEN, a citizen of the United States, residing at Hutchinson, in the county of Reno and State of Kansas, have invented a new and useful Hollow Steel Tie, of which the following is a specification.

This invention has relation to hollow steel ties and it consists in the novel construction and arrangement of its parts as hereinafter shown and described.

10. The object of the invention is to provide a tie of the character indicated which is light in construction and of a durable nature. Said tie is provided in its top and vertical sides with openings through which ballast may be passed into the body of the tie for the purpose of weighting the same firmly upon the track bed. The bottom of the tie is of greatest longitudinal dimension and the top of the tie possesses the shortest longitudinal dimension while the connecting vertical sides are provided with chamfered ends with orifices in the vicinity thereof in which the point of an implement may be inserted for handling the ties. The vertical sides and bottom of the tie at those portions occurring under the top of the tie upon which the rail bases rest are corrugated or thickened for the purpose of bracing the structure and adding materially to the rigidity and strength thereof. For securing the rails to the ties washers having laterally extending lugs are bolted to the top of the tie with the lugs projecting over the edges of the bases of the flanges of the rail.

30. In the accompanying drawing:—Figure 1 is a perspective view of the tie, and Fig. 2 is a longitudinal sectional view of the same.

The tie comprises the top side 1, the bottom side 2 and the connecting vertical sides 3, 3. Of the said sides the top 1 is the shortest while the bottom 2 is the longest and the ends of the sides 3 are chamfered as at 4. The bottom 2 is perforated at 2' while the top 1 is provided at intermediate points with the openings 5 and the sides 3 at the intermediate points with the openings 6. The sides 3 and the bottom 2 are provided at

portions occurring immediately below the portions of the top 1 upon which the track rails rest with corrugations or thickened portions 7 which add materially to the strength of the structure making the same durable and inflexible and at the same time presenting shoulders to the ballast of the track bed which tend to prevent longitudinal movement of the tie. The track ballast is filled in to the tie through the openings 5 and 6 and thus the tie is weighted upon the track bed. The sides 3 are provided with perforations 8 located in the vicinity of the ends thereof and which are adapted to receive the end of a pick or other implement when the tie is handled. The perforations 2' serve similar purposes. The washers 9 are bolted to the top 1 of the side and are provided with the laterally disposed lugs 10 which are adapted to project over the edges of the bases of the track rails and secure the same upon the ties.

Having described my invention what I claim as new and desire to secure by Letters-Patent is:—

1. A hollow metallic tie having rectangularly disposed sides, the top side of which is provided with depressed rail-bearing surfaces and the vertical and bottom sides having thickened portions located under the said rail-bearing surfaces. 60

2. A hollow metallic tie having rectangularly disposed sides, the vertical side having portions which increase in thickness from the top to the bottom side and the bottom side having thickened portions which merge at their end with the thickened portions upon the vertical sides. 65

3. A hollow metallic tie having rectangularly disposed sides, the top side of which is provided with depressed rail bearing surfaces, the vertical sides having portions which increase in thickness from the top to the bottom side and the bottom side having thickened portions which merge at their ends with the thickened portions upon the vertical sides, said thickened portions being located under said rail bearing surfaces. 70

In testimony that I claim the foregoing as my own, I have hereto affixed my signature in the presence of two witnesses.

HARRY EVERETT McMULLEN.
